UNITED STATES PATENT OFFICE.

GEORGE M. JOHNSON, OF McDONALD, PENNSYLVANIA.

SAFETY HORN-BLOCK AND TRIPPING MECHANISM.

1,364,627.

Specification of Letters Patent.

Patented Jan. 4, 1921.

Application filed March 27, 1919, Serial No. 285,158. Renewed June 2, 1920. Serial No. 386,046.

To all whom it may concern:

Be it known that GEORGE M. JOHNSON, a citizen of the United States, residing at McDonald, in the county of Washington and 5 State of Pennsylvania, has invented certain new and useful Improvements in Safety Horn-Blocks and Tripping Mechanism, of which the following is a specification.

This invention relates to safety horn blocks and tripping mechanism therefor, particularly adapted for use in connection with mine cages, although it is to be understood that the invention is adapted for any purposes wherein it is found applicable, and 10 has for its object to provide, in a manner as hereinafter set forth, means associated with a mine cage to arrest a car or cars when run thereon to prevent the car or cars from being accidentally dislodged therefrom until 15 said means is released, and to further provide, for the locking of the car or cars on the cage to prevent the dislodgment thereof when the cage is tilted.

A further object of the invention is to 25 provide in a manner as hereinafter set forth, stop blocks for engagement with the front and rear wheels of a car, when run upon a cage, to lock the car on the cage, and to further provide means associated with the 30 blocks to cushion the same when impacted upon by the wheels of the car whereby the life of the blocks is increased and damage to the wheels reduced to a minimum.

A further object of the invention is to 35 provide in a manner as hereinafter set forth, front and rear slideable stop blocks for use on a mine cage to lock a car thereon, said front and rear blocks sliding longitudinally of the cage and in unison, and to further 40 provide means for connecting a front to a rear stop block whereby said blocks will shift in unison and further freely slide or shift in case the central portion of the cage body buckles.

45 A further object of the invention is to provide means whereby the front or forward stop blocks are automatically shifted to released position, when a car or cars is or are run on a mine cage when the cage is arranged stationary at a landing of the mine 50 shaft, and without depending upon the movement of the cage, to release the blocks.

A further object of the invention is to 55 provide, in a manner as hereinafter set forth, a horn block mechanism for the purpose referred to, constructed and arranged

relatively to the track rails to prevent clogging of the blocks so as not to interfere with the operative movement thereof, such mechanism being simple in its construction and arrangement, strong, durable, efficient and convenient in its use, readily set up and comparatively inexpensive.

With the foregoing and other objects in view this invention consists of the novel 60 construction, combination and arrangement of parts as hereinafter more specifically described and illustrated in the accompanying drawings, wherein is shown an embodiment of the invention but it is to be understood 65 that changes, variations and modifications can be resorted to which come within the scope of the claims hereunto appended.

In the drawings wherein like reference characters denote corresponding parts 70 throughout the several views:

Figure 1 is a side elevation of a mine cage showing the adaptation therewith of a horn block mechanism in accordance with this invention.

Fig. 2 is a top plan view of a horn block mechanism.

Referring to the drawings in detail 1 denotes a mine cage, having its bottom 2, provided with a pair of trackrails 3.

Upon the bottom 2, exterior of each of the trackrails is fixedly secured rectangular supports which are indicated by the reference characters 4, 5, 6, 7, each of said supports extends above the tread of the trackrail and 80 is formed centrally with a rectangular slot or opening 8. Each support at one end has a bore 9, which opens into one end of the slot 8 and each support at its other end has a bore 10, which opens into the other end of 85 the slot 8.

Slidably mounted in the bores 9, 10, and extending across the slot 8, of the support 4, is a slide rod, 11, which projects inwardly from the inner end of the support 4. 100 Mounted in the bores 9, 10, and extending across the slot 8, of the support 5, is a slide rod 12, which projects inwardly from said support 5. Slidably mounted in the bores 9, 10, and extending across the slot 8, of the 105 support 6, is a slide rod 13, which projects forwardly from said support 6.

Slidably mounted in the bores 9, 10, and extending across the slot 8, of the support 7, is a slide rod 13^a, which projects forwardly 110 from said support 7.

The forward stop blocks which are fixedly

secured to the rods 11, 12, extend into the supports 4 and 5. Each of the forward stop blocks consists of a base 14, of less length than the length of the slot 8, and which is formed with an opening through which extends a slide rod. The base is fixedly secured to the slide rod. Projecting upwardly from the base 14, is an arm or horn 16, formed with the working surface 10 or surfaces 17, which engage and overlap the tread of a wheel 18^a. The working surfaces are disposed at an angle with respect to the arm 16.

One of the forward stop blocks has its base 14, at its inner end provided with a depending crank and the base 14, of the other forward stop block has its forward end provided with a depending crank. The cranks are indicated at 18, and extend down through openings or slots 19, formed in the bottom 2.

Each of the slide rods 11, 12, is formed with a shackle or clevis 20, and is further provided with an adjustable nut 21, and washer 22.

Surrounding the slide rods 11, 12, and interposed between the washers 22, and supports 4, 5, are cushioning elements 23, in the form of coiled compression springs.

The rear stop blocks which are indicated at 24, 25, are similar in construction to the forward stop blocks with this exception, that the rear end of the bases 26, of said rear stop blocks have depending arms 27, which extend down through the openings 28, and have expanding springs 29, bearing thereagainst for maintaining the rear stop blocks normally in position to extend over the tread of the track rails so as to be in the path of the wheels of the car. The expanding springs 29, are secured in any suitable manner to the bottom 2.

The rear stop blocks 24, 25, are fixedly secured respectively to the slide rods 13, 13^a, these latter are provided with shackles or clevises 30, adjusting nuts 31, washers 32, and cushioning elements 33, in the form of coiled extensible springs which are mounted on the rods 13, 13^a, between the washers 32 and the supports 6, 7. The rear stop blocks are set up whereby they can be automatically shifted by the wheels of the car when the cage is run upon the rails 3, and through the action of the springs 29, will automatically shift over the rails 3, after the wheels have passed the blocks, restoring the blocks to operative position to lock the rear wheels of the car.

The slide rod 11, is connected to the slide rod 13, by a flexible element 34, preferably a chain and the slide rod 12, is connected to the slide rod 13^a, by a flexible element 35, preferably a chain. By this construction when the forward stop blocks are impacted upon by the wheels of the car they will be

shifted longitudinally with respect to the cage and owing to the connections between the slide rods the rear stop blocks will be carried therewith. The sliding movement of the forward stop blocks and the rear stop blocks will be against the action of the springs 23, 33, thereby providing a cushion for the blocks.

The springs 23, 33, will tend to maintain the stop blocks in close contact with the treads of the wheels of the car.

The forward stop blocks are shifted to released position to allow the car to be run off the cage, through the medium of a pair of actuating rods 36, 37, which are connected to the crank arms 18. Extending down through the bottom 2, of the cage 1, is a vertically disposed shaft 38, provided on its lower end with a lever arm 39, which is connected as at 40 to the rod 36, and as 40, to the rod 37. The upper end of the shaft 38, has a crank 42, which is connected as at 43, to an operating bar 44, mounted in supports 45, secured on the bottom 2.

The operating bar 44, is shifted by any suitable mechanism arranged at the landing.

When the bar 44, is shifted the forward stop blocks are swung clear of the wheels of the car, and such operation is had against the action of a coiled spring 46, which has one end secured to the extended end 47 of the lever arm 39, and its other end secured to the bottom of the cage.

The spring 46, restores the forward stop blocks to normal position which is in the path of travel of the car wheel.

The flexible connections between the slide rods provide means to overcome binding of the slide rods when the central part of the body of the cage buckles.

If the forward stop blocks and the rear stop blocks were mounted on a single rod the buckling of the cage at its center would buckle the rod end such action binding the same and retarding its sliding movement, thus preventing the simultaneous cushioning action to the front and rear blocks as they would be unable to shift longitudinally in unison.

What I claim is:

1. A horn block mechanism for mine cages comprising a pair of automatically operable rear stop blocks normally in operative position, a pair of forward stop blocks normally in operative position, a shifting mechanism for moving said forward stop blocks to inoperative position, and a cushioned longitudinally movable and oscillatory sliding element fixed to each of said stop blocks, each of said blocks sliding and oscillating with its respective sliding element, and means for flexibly connecting the slide elements of the rear stop blocks to the slide elements of the forward stop blocks.

2. A horn block mechanism for mine cages

comprising a pair of automatically operable rear stop blocks normally in operative position, a pair of forward stop blocks normally in operation position, a shifting mechanism 5 for moving said forward stop blocks to inoperative position, and a cushioned longitudinally movable and oscillatory sliding element fixed to each of said blocks, each of said blocks sliding and oscillating with its 10 respective sliding element, and means for flexibly connecting the slide elements of the rear stop blocks to the slide elements of the forward stop blocks, and a stationary support for each of said elements, said elements 15 each projecting from one end of its respective support.

3. A horn block mechanism for mine cages comprising a pair of oscillatory forward stop blocks, a pair of oscillatory rear stop 20 blocks, a cushioned and longitudinally slideable element for each of said blocks, each of said blocks fixed to and moving with its re-

spective element, and means for connecting the slideable elements for the rear stop blocks to the slideable elements for the front 25 stop blocks whereby said front and rear stop blocks will slide in unison.

4. A horn block mechanism for mine cages comprising a pair of front and a pair of rear spring controlled slide elements, means 30 for flexibly connecting said rear elements to said front elements, and a stop block fixedly secured to and moving with each of said elements.

5. A horn block mechanism for mine cages 35 comprising a pair of front and a pair of rear spring controlled oscillatory slide elements, means for connecting said rear elements to said front elements, and a stop block fixedly secured to and moving with each of said 40 elements.

In testimony whereof I affix my signature.

GEORGE M. JOHNSON.
